US0D1106322S

(12) United States Design Patent (10) Patent No.: US D1,106,322 S
 Klosky et al. (45) Date of Patent:  Dec. 16, 2025

(54) FOLDER STACK(71) Applicant: Ideastream Consumer Products, LLC,
Cleveland, OH (US)(72) Inventors: Eric F. Klosky, Chagrin Falls, OH
(US); Vincent J. Thomson, Avon Lake,
OH (US); Anthony J. DeCarlo, Parma,
OH (US); Daniel V. Perella, Hudson,
OH (US)(73) Assignee: Ideastream Consumer Products, LLC,
Cleveland, OH (US)() Term: 15 Years(21) Appl. No.: 29/778,943(22) Filed: Apr. 15, 2021*Related U.S. Application Data

(60) Continuation-in-part of application No. 29/594,432, filed on Feb. 17, 2017, now Pat. No. Des. 944,324, which is a continuation-in-part of application No. 29/537,202, filed on Aug. 24, 2015, now Pat. No. Des. 790,628, which is a division of application No. 29/427,218, filed on Jul. 16, 2012, now Pat. No. Des. 739,892, application No. 29/778,943 is a continuation-in-part of application No. 15/633,066, filed on Jun. 26, 2017, now abandoned, which is a continuation of application No. 29/537,202, filed on Aug. 24, 2015, now Pat. No. Des. 790,628, which is a division of application No. 29/427,218, filed on Jul. 16, 2012, now Pat. No. Des. 739,892.

CLAIM

The ornamental design for a folder stack, as shown and described.

DESCRIPTION

FIG. 1 is a front view of a folder stack; and, FIG. 2 is a rear view thereof.

We disclaim the background and surface ornamentation. The material thicknesses in the top, bottom, left side, and right side views have been slightly exaggerated.

1 Claim, 2 Drawing Sheets# US D1,106,322 S
